US00D708317S

(12) **United States Design Patent**
Schneider et al.

(10) **Patent No.:** **US D708,317 S**
(45) **Date of Patent:** **** Jul. 1, 2014**

(54) **AUTOINJECTOR**

(75) Inventors: **Jared Schneider**, Cranston, RI (US);
Mark Joseph Guarraia, Cranston, RI (US); **Margaux Frances Boyaval**, Warwick, RI (US); **Ryan James Shafer**, Whitinsville, MA (US); **Louis Petit**, Grenoble (FR)

(73) Assignee: **Becton, Dickinson and Company**, Franklin Lakes, NJ (US)

(**) Term: **14 Years**

(21) Appl. No.: **29/418,261**

(22) Filed: **Apr. 13, 2012**

(51) **LOC (10) Cl.** **24-02**

(52) **U.S. Cl.**

USPC **D24/113**

(57) **CLAIM**

The ornamental design for an autoinjector, as shown and described.

DESCRIPTION

FIG. 1 is a perspective view of an embodiment of an autoinjector showing our new design, with a cap shown in a secured position;

FIG. 2 is a front elevational view of the autoinjector shown in FIG. 1;

FIG. 3 is a left side elevational view of the autoinjector shown in FIG. 1;

FIG. 4 is a top view of the autoinjector shown in FIG. 1;

FIG. 5 is a bottom view of the autoinjector shown in FIG. 1;

FIG. 6 is a right side elevational view of the autoinjector shown in FIG. 1; and,

FIG. 7 is a rear elevational view of the autoinjector shown in FIG. 1.

The broken line showing of parts of the drawings is included for the purpose of illustrating use and environment and forms no part of the claimed design.

1 Claim, 3 Drawing Sheets
